UNITED STATES PATENT OFFICE.

LEE J. TAYLOR, OF NEW BERN, NORTH CAROLINA.

DESIGN FOR A BOTTLE.

Application filed August 6, 1924. Serial No. 10,388. Term of patent 7 years.

To all whom it may concern:

Be it known that I, LEE J. TAYLOR, a citizen of the United States, residing at New Bern, in the county of Craven, and State of North Carolina, have invented a new, original, and ornamental Design for Bottles, of which the following is a specification, reference being had to the accompanying drawing, forming a part thereof.

Figure 1 is a view in elevation of a bottle, showing my new design.

Figure 2 is a sectional view on line 2—2 of Figure 1.

I claim:

The ornamental design for a bottle, as shown.

LEE J. TAYLOR.
